UNITED STATES PATENT OFFICE.

GAVIN RITCHIE, JR., OF BATTLE CREEK, MICHIGAN, ASSIGNOR OF THREE-FOURTHS
TO CHARLES L. BRALEY, OF CHICAGO, ILLINOIS.

PRESSING AND IRONING MACHINE.

1,358,879.

Specification of Letters Patent. Patented Nov. 16, 1920.

Application filed July 29, 1919. Serial No. 314,043.

To all whom it may concern:

Be it known that I, GAVIN RITCHIE, Jr., citizen of the United States, residing at Battle Creek, Michigan, have invented certain new and useful Improvements in Pressing and Ironing Machines, of which the following is a specification.

This invention relates to improvements in pressing and ironing machines.

10 The main objects of this invention are:

First, to provide a combined pressing and ironing machine which is very efficient and convenient in operation.

Second, to provide a combined pressing and ironing machine which is compact, and simple and economical in structure.

Third, to provide in an ironing machine an improved feed means.

Fourth, to provide in an ironing machine means for automatically raising and lowering the feed roller, and stopping the motor.

Fifth, to provide an improved mounting means for a pressing buck whereby the pressure is equalized.

25 Further objects, and objects relating to details and economies of construction and operation will definitely appear from the detailed description to follow.

I accomplish the objects of my invention by the devices and means described in the following specification. The invention is clearly defined and pointed out in the claims.

30 A structure which is a preferred embodiment of my invention is illustrated in the accompanying drawing forming a part of this specification, in which:

Figure I is a side elevation of a structure embodying the features of my invention, parts being shown in vertical section in order to better illustrate the structural details thereof.

40 Fig. II is an end view looking from the right of Fig. I, the pressing buck being shown in its retracted position by the dotted lines.

Fig. III is an enlarged detail side elevation with the pressing roller carriage in its elevated position.

45 Fig. IV is a detail vertical central section on a line corresponding to line 4-4 of Fig. I.

Fig. V is a horizontal section on a line corresponding to line 5-5 of Fig. II.

Fig. VI is a detail view partially in vertical section on a line corresponding to line 55 6-6 of Fig. V.

Fig. VII is a detail view partially in vertical section on a line corresponding to line 7-7 of Fig. I, showing details of the frame structure.

Fig. VIII is a detail view of the face of the feed board.

Referring to the drawings, the base 1 is preferably a casting comprising a longitudinal centrally disposed member 2, and end 65 members 3. The base is provided with sockets 4 for the tubular uprights 5 which are preferably formed of sections of pipe, the same being secured in the sockets by the pins 6.

70 Braces 7 extend from the T-shaped top pieces 8 engaged in the upper ends of the uprights 5—see Fig. II and Fig. VII.

The steam chest or ironing shoe 9 is mounted on brackets 10 sleeved upon and 75 secured to the uprights 5. This steam chest is provided with a concave ironing face 11 on its upper side, and a downwardly facing pressing face 12 on its under side.

The feed and pressing roller 13 is provided with a shaft 14 carried by a carriage or movable support consisting of the tubular end members 15, slidably mounted on the uprights and connected by the cross bar 16, the end members being provided with bearings 85 17 at their lower ends for the shaft 14, and the upright being vertically slotted at 18 to receive the shaft and permit the vertical movement of the carriage.

80 The driving shaft 19 is mounted on the carriage above the cross bar 16, the uprights being slotted to provide vertical movement of this shaft.

The motor 20 is mounted on a bracket 21 carried by one of the end members 15, the motor being geared to the driving shaft 19 by the gear 22 and the pinion 23. The driving shaft 19 is connected to the roller shaft 14 by a train of gears consisting of gears 24, 25, 26 and 27. As the details of these 100 gears form no part of this invention, they are not further described herein.

An adjusting weight 28 is mounted on the bar 16 so that it may be adjusted thereon to secure a substantially uniform pressure on 105 the feed roller.

- To raise the roller 13, the shaft 14 is provided with cams 29 arranged to coact with the sliding abutments 30, mounted on the frame below the cams. The abutments are 5 provided with return springs 31, but these springs are not of sufficient strength to retract the abutments while they are engaged by the cams 29. As soon, however, as they are relieved of the load by the rotation of 10 the cams, the springs retract them. They are connected by a cross rod 32 which serves as a handle, the handle being arranged to be manipulated from the feed board side of the machine.
- 15 When the handle is actuated to project the abutments 30, they lie in the path of the cams so that they are engaged thereby and when the high point of the cams is reached, the carriage is elevated bringing the motor control contacts 32', shown conventionally, into engagement and stopping the motor with the carriage in its elevated position. In the event of its being desired to elevate the carriage by hand, as for instance, if the 20 motor has stopped, I provide the shaft 19 with a crank, shown conventionally, at 33. The motor is started by means of a hand operated switch operatively associated with the contacts 32' to break the short circuit.
- 25 On the starting of the motor with the carriage in its elevated position, the springs 31 return the abutments to their retracted or inoperative position as soon as they are released on the dwell of the cams. The weight 30 of the floating parts provides the pressure, no springs or levers or like pressure means being required. Additional weights 28 may be provided, if desired.
- The feed board 34 is pivoted at 35 so that 35 its face 36 may be swung to and from the feed roller 13, the feed board face 36 being curved to correspond to the feed roller and engage or coact with the same at a point just above the steam chest 9. This feed board is provided with a suction chamber 37, its face being perforated as indicated in Fig. VIII, so that the articles to be ironed are held against the face. This is a great convenience in arranging articles on the 40 feed board, and it also assists in straightening or smoothing the articles as they are drawn forward over the feed board by the feed roller.
- The suction is secured from a small motor 45 driven pump 38 connected with the suction chamber by the vertical pipe 39. A shelf 40 is arranged below the feed board for supporting the articles in this position.
- The switch board 41 is preferably arranged at one end of the feed board for the 50 convenience of the operator. I do not attempt to illustrate the electrical wiring or connections as such details form no part of this invention.
- 55 To return the articles to the operator,

where it is desired to pass them through the machine again, I provide a gate or return guide 42 which is pivoted at 43 above the roller 13, the edge of the guide being adapted to swing down against the ironing shoe 70 so that the articles are guided around the roller and delivered at the front or may be taken off by the operator at the feed board.

The pressing buck 44 is mounted for swinging and vertical adjustment to coact 75 with the pressing face 12 of the steam chest. The supporting standard 45 of the pressing buck is pivotally mounted at 46 on a link 47 pivoted at 48. The actuating lever 49 is mounted on this same pivot 48, and is provided with a roller 50 which engages the inclined cam end 51 of the link as the lever is forced downwardly so that a sort of toggle cam action is afforded to elevate the standard and apply pressure thereto. A 80 spring buffer 52 is provided for the lever.

The standard is supported for lateral swinging movement by the yoke 53 having spring buffers 54 and 55 at the ends thereof. When in its forward position, as shown by 90 dotted lines in Fig. II, the articles to be pressed may be conveniently arranged upon the buck which is then swung rearwardly under the steam chest and actuated by means of the foot lever 49. A comparatively short stroke of the lever is all that is required, and sufficient power is exerted with but little effort on the part of the operator.

To permit the pressing buck to adjust 100 itself to the steam chest or equalize the pressure thereon, the pressing buck is provided with a centrally disposed threaded shank or screw 56 on which the spherical support 57 is threaded. This support rests 105 on the upper end of the tubular standard. The shank or screw 56 has a friction means engaging the standard consisting of a friction disk 58 arranged between two clamping disks 59, threaded upon the screw, the friction disk projecting beyond the edges of the disks 59 to engage the standard,—see Fig. IV. By this means the pressing buck is 110 adjustably supported for the purposes described.

115 My improved combined ironing and pressing machine is very compact; it is comparatively simple and economical in structure, and is very efficient and at the same time very convenient to use.

I have not attempted to illustrate or describe certain modifications or adaptations which I contemplate as I believe that disclosure made will enable those skilled in the art to which this invention relates to embody or adapt the same as may be desired to meet the different working conditions or special work which it may be intended to perform.

120 My improved combination machine is well 130

adapted for use in laundries for carrying out the so-called "family methods," that is, where the entire laundry of one customer is handled as a batch or job, as distinguished from the method where the articles of various customers are marked and thrown together to be afterward sorted. The machine is also well adapted for family use.

Having thus described my invention, what I claim as new and desire to secure by Letters Patent, is:

1. In an ironing machine, the combination of a frame comprising a base, a pair of uprights, braces extending from the upper ends of said uprights to said base, a chest or ironing shoe mounted on said uprights, a coacting feed and pressing roller, a shaft therefor, a feed roller carriage comprising a pair of end members on which said shaft is mounted sleeved upon said uprights, a driving motor mounted on one of said end members, a driving shaft mounted on said end members, a train of gears mounted on the other end member and connecting said driving and feed roller shafts, a pair of lifting cams on said roller shaft, abutment slides mounted on said uprights to coact with said cams, return springs for said slides, means for simultaneously actuating said slides to operative position, and a motor control means for stopping the motor when said roller carriage is in its elevated position.

2. In an ironing machine, the combination of a frame comprising a base, a pair of uprights, braces extending from the upper ends of said uprights to said base, a chest or ironing shoe mounted on said uprights, a coacting feed and pressing roller, a shaft therefor, a feed roller carriage comprising a pair of end members on which said shaft is mounted sleeved upon said uprights, a driving motor mounted on one of said end members, a driving shaft mounted on said end members, a train of gears mounted on the other end member and connecting said driving and feed roller shafts, and means for actuating said carriage for lifting the roller from the iron shoe.

3. In an ironing machine, the combination of a frame comprising a base, a pair of uprights, braces extending from the upper ends of said uprights to said base, a chest or ironing shoe mounted on said uprights, a coacting feed and pressing roller, a shaft therefor, a feed roller carriage comprising a pair of end members on which said shaft is mounted sleeved upon said uprights and a cross bar connecting the upper ends of said end members, a driving motor mounted on one of said end members, a driving shaft mounted on said end members above said cross bar, a train of gears mounted on the other end member and connecting said driving and feed roller shafts, a weight

adjustably mounted on said cross bar and means for elevating said carriage for separating the roller from the shoe.

4. In an ironing machine, the combination of a frame comprising a pair of uprights, an ironing shoe, a feed roller, a shaft therefor, a feed roller carriage comprising a pair of end members on which said shaft is mounted slidable upon said uprights, a driving motor mounted on one of said end members, a driving shaft mounted on said roller carriage, a train of gears mounted on the other end member connecting said driving and feed roller shafts, a pair of lifting cams on said roller shaft, abutment slides mounted to coact with said cams, means for actuating said slides to operative position, and a motor control means for stopping the motor when said roller carriage is in its elevated position.

5. In an ironing machine, the combination of a frame comprising a pair of uprights, an ironing shoe, a feed roller, a shaft therefor, a feed roller carriage comprising a pair of end members on which said shaft is mounted slidable upon said uprights, a driving motor mounted on one of said end members, a driving shaft mounted on said roller carriage, a train of gears mounted on the other end member connecting said driving and feed roller shafts, and means for actuating said carriage for lifting the roller from the iron shoe.

6. In an ironing machine, the combination of a frame comprising a pair of uprights, an ironing shoe, a feed roller, a shaft therefor, a feed roller carriage comprising a pair of end members on which said shaft is mounted slidable upon said uprights and a cross bar connecting said end members, a driving motor mounted on one of said end members, a driving shaft mounted on said roller carriage, a train of gears mounted on the other end member connecting said driving and feed roller shafts, a weight adjustably mounted on said cross bar and means for elevating said carriage for separating the roller.

7. In an ironing machine, the combination of a frame, a chest or ironing shoe mounted on said frame, a coacting feed roller, a shaft therefor, a feed roller carriage, a driving motor mounted on said carriage, driving connections therefrom to said roller shaft on said carriage, a weight adjustably mounted on said carriage, means for actuating said carriage for lifting the roller from the iron shoe, and a motor control means for stopping the motor when said roller carriage is in its elevated position.

8. In an ironing machine, the combination of a frame, a chest or ironing shoe mounted on said frame, a coacting feed roller, a shaft therefor, a feed roller carriage, a driving

motor mounted on said carriage, driving connections therefrom to said roller shaft on said carriage, a weight adjustably mounted on said carriage, and means for actuating 5 said carriage for lifting the roller from the iron shoe.

9. In an ironing machine, the combination of a frame, a chest or ironing shoe mounted on said frame, a coacting feed roller, a shaft 10 therefor, a feed roller carriage, a driving motor, driving connections therefrom to said roller shaft, a lifting cam on said roller shaft, an abutment slide mounted to coact with said cam, means for actuating said 15 slide to operative position, and a motor control means for stopping the motor when said roller carriage is in its elevated position.

10. In a combined ironing and pressing machine, the combination of a chest or 20 ironing shoe having a pressing face on its under side, a pressing buck, a supporting standard therefor, a pivoted supporting link for said standard having a cam face thereon, and an actuating lever mounted on said pivoted link and provided with a pin coacting 25 with the cam face of said link.

11. The combination of a heated member having a pressing face on its under side, a 30 pressing buck, a supporting standard therefor, a pivoted supporting link for said stand-

ard having a cam thereon, and an actuating lever mounted on said pivoted link and provided with a pin coacting with the cam face of said link.

12. In a combined ironing and pressing 35 machine, the combination of an ironing shoe having a pressing face on its under side, a feed roller coacting with said ironing shoe, an adjustable pressing buck, and means for applying pressure to said buck.

13. In an ironing machine, the combination of a steam chest or concave, a coacting feed and pressing roller, and a feed board mounted for adjustment to and from said feed and pressing roller, and a feed board 45 therein with a foraminated face curved to coact with the feed roller above the steam chest.

14. In an ironing machine, the combination of a feed roller, a feed board adjustably 50 supported relative to said feed roller and having a suction chamber therein with a foraminated face opposed to said feed roller.

In witness whereof I have hereunto set my hand and seal in the presence of two witnesses. 55

GAVIN RITCHIE, JR. [L.S.]
